United States Patent Office.

HENRY KAGY, OF PHILADELPHIA, PENNSYLVANIA, ASSIGNOR TO THOMAS POTTER, SON & CO., OF SAME PLACE.

Design No. 4,406, dated October 11, 1870.

DESIGN FOR AN OIL-CLOTH PATTERN.

The Schedule referred to in these Letters Patent and making part of the same

I, HENRY KAGY, a native of Switzerland, but at present residing in Philadelphia, county of Philadelphia, State of Pennsylvania, have invented or produced a Design for an Oil-cloth Pattern, of which the following is a specification.

Design for an Oil-Cloth Pattern.

The figure in the accompanying drawing illustrates, partly in outline and partly filled in with ornaments, my design for an oil-cloth pattern, the main characteristic of which consists of the peculiar arrangement in respect to each other of the square tablets A, oblong spaces B, and square figures D, the disposition of these features being clearly illustrated in outline.

The tablet A has an ornamental border, x, and a central ornament, sufficient of which is illustrated in the drawing to define its character.

Each oblong space B is ornamented throughout

with figures y, and the ornamentation of the square figures D is too clearly shown to need explanation.

I claim—

1. Irrespective of any ornamentation, an oil-cloth pattern, consisting of square tablets A, oblong spaces B, and square figures D, formed and arranged in respect to each other, in the manner illustrated in the outline.

2. The tablets A, ornamented as shown.

3. The oblong spaces B, ornamented as illustrated in the drawing.

4. The square figures D, ornamented as shown.

In testimony whereof, I have signed my name to this specification in the presence of two subscribers as witnesses.

HENRY KAGY.
